(57) **CLAIM**

The ornamental design for a blade cartridge tray, as shown and described.

DESCRIPTION

FIG. 1 is a top, front, left side perspective view of a blade cartridge tray according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, left side perspective view thereof showing a cover of the blade cartridge tray in a closed position.

The long-dash-short dash broken lines represent boundaries of the claimed design and form no part thereof. All other broken lines represent portions of the blade cartridge tray that form no part of the claimed design.

The blade cartridge tray is shown with a symbolic break in its length. The appearance of any portion of the article between the break lines forms no part of the claimed design.
